(57) **CLAIM**

We claim the ornamental design for a medical insertion device, as shown and described.

DESCRIPTION

FIG. 1 is a left side elevational view of the present invention;

FIG. 2 is a front side elevational view thereof;

FIG. 3 is a top plan view thereof;

FIG. 4 is a right side elevational view thereof;

FIG. 5 is a top perspective view thereof; and,

FIG. 6 is a bottom side perspective view thereof.

The ornamental design which is claimed is shown in solid lines in the drawings. Any broken lines in the drawings are for illustrative purposes only and form no part of the claimed design.

The portions of the article in broken lines are shown for illustrative purposes only and form no part of the claimed design.
